(57) **CLAIM**

The ornamental design for a handle for brush or other implement, as shown and described.

DESCRIPTION

FIG. 1 is a right perspective view of a handle for brush or other implement embodying my new design, an illustrative brush end being shown in broken lines;

FIG. 2 is a top plan view thereof;

FIG. 3 is a right side elevational view thereof, the left side elevational view being a mirror image thereof;

FIG. 4 is a bottom plan view thereof;

FIG. 5 is a front end view thereof;

FIG. 6 is a rear end view thereof;

FIG. 7 is a right perspective view of a second embodiment of the handle for brush or other implement showing my new design, an illustrative squeegee end being shown in broken lines;

FIG. 8 is a top plan view of the second embodiment;

FIG. 9 is a right side elevational view of the second embodiment;

FIG. 10 is a bottom plan view of the second embodiment;

FIG. 11 is a front end view second embodiment; and,

FIG. 12 is a rear end view of the second embodiment.

The structures shown in broken lines form no part of the claimed design.
